UNITED STATES PATENT OFFICE.

FRANK ROBERSON, OF GARY, INDIANA, ASSIGNOR TO GENERAL ELECTRIC COMPANY,
A CORPORATION OF NEW YORK.

CIRCUIT INTERRUPTER.

Application filed April 9, 1926. Serial No. 100,976.

My invention relates to improvements in dependently movable switch members in circuit interrupters, particularly automatic overload circuit interrupters of the high speed flux shifting type that ordinarily respond 5 only to excessive currents flowing in a predetermined direction. The improvements provided by the present invention enable a circuit interrupter of the above type to protect alternating current circuits, as well as direct current circuits in which current may 10 flow in either direction.

More specifically the present invention is an improvement upon the type of high speed flux shifting circuit interrupter described 15 and claimed in my Patent No. 1,566,122 of December 15, 1925. In my patented type of circuit interrupter a pair of cooperating movable circuit controlling members are operable into circuit closing engagement 20 and each is strongly biased to the circuit interrupting position. An electromagnet is provided with separate poles for electromagnetically holding each switch member in the circuit closing position. The release 25 of each switch member is controlled by a common magnetized winding or current conductor which is arranged to shift the flux of the holding electromagnet so as to instantly decrease the magnetic holding effect 30 of all the poles of the holding electromagnet when a current of excessive value flows in a predetermined direction through the releasing winding or conductor.

In accordance with my present invention 35 the flux shifting winding or conductor is arranged to effect the release of one or the other of the pair of cooperating circuit controlling members depending upon the direction in which the excessive current flows 40 through the releasing winding or conductor. In this way a high speed circuit interrupter of the type described in my above noted patent is rendered capable of affording protection to alternating current circuits or to direct current circuits in which the current 45 may flow in either direction since at least one of the circuit controlling members is always released to move out of engagement with the cooperating member upon a predetermined current flow in either direction 50 in the circuit controlled by the interrupter.

Briefly, in carrying the present invention 55 into effect in a circuit interrupter having a holding electromagnet with separate pairs of poles for maintaining the cooperating in-

circuit closing engagement, the releasing conductor or winding is associated with the separate poles of the holding electromagnet in such manner as to act differentially or oppositely thereupon. That is, with the current flowing through the releasing conductor or winding the action upon one pair of the poles of the holding electromagnet is such as to release the switch member held thereby, while 60 the action upon the other pair of poles is such as to more firmly hold the switch member cooperating therewith. On the other hand, with current flowing through the releasing conductor or winding in the opposite 65 or reverse direction, the relative action upon the several poles of the holding electromagnet is also reversed so that the other switch member is released while the first switch member is held more firmly in engagement 70 with the cooperating pole of the holding electromagnet. Thus irrespective of the direction in which current is supplied to the releasing conductor or winding one of the 75 switch members always is released when the 80 current flowing in either direction exceeds a predetermined value.

Figs. 1 and 2 of the accompanying drawing diagrammatically illustrate an embodiment of the present invention in a high speed 85 electromagnetic circuit interrupter of the type disclosed in my prior Patent No. 1,566,122 of December 15, 1925. Figs. 3 and 4 show diagrammatically a modification of the arrangement illustrated in Figs. 1 and 2. 90

Referring to Fig. 1, the circuit interrupter embodying my invention is of the general form described and claimed in my prior patent previously mentioned, and consists essentially of two cooperating independently 95 movable switch members 10 and 11 which are each strongly biased to the circuit interrupting position by means of the biasing springs 12 and 13 respectively and are pivotally mounted to rotate about the pivots 100 14 and 15. The movable switch members are provided with suitable yielding contacts 16 and 17 which are arranged to move into circuit closing engagement when the switch arms 10 and 11 are operated to their 105 respective circuit closing positions.

As more fully set forth in my prior patent, the switch members 10 and 11 are held in the circuit closing position by the magnetic attraction of the magnetic members 18 110

and 19, which are carried respectively by the switch members 10 and 11 with the cooperating poles 20 and 21 of the holding electromagnet 22. The magnetizing winding 23 of the holding electromagnet sets up a flux in the magnetic structure thereof in such direction that the poles 20 and 21 are of corresponding polarity as indicated by the notations N and S in the drawing. The magnetic attraction between the magnetic members 18 and 19 and the cooperating poles 20 and 21 serves to hold the switch members 10 and 11 in the circuit closing position when operated thereto through the agency of suitable closing mechanism such as the combined manual and electromagnetic closing devices 24 and 25 illustrated in the drawing.

The release of the magnetic members 18 and 19, and consequently of the corresponding switch members 10 and 11, is controlled by the releasing conductor or winding 26 which is connected in the circuit controller by the interrupter extending from the terminal 27 through a suitable flexible connector to the contact 17, thence through the cooperating contact 16 and a similar flexible connector connecting the latter to the releasing conductor 26. The releasing conductor 26 is offset or looped as more fully shown in Fig. 2 to form a Z or S shaped "bucking bar" in cooperating magnetic relation with the pairs of poles 20 and 21 of the holding electromagnet 20 and is connected to the other terminal 28 of the circuit interrupter.

As shown more clearly in Fig. 2, the magnetic relation of the offset portion of "bucking bar" 26 with the poles 20 and 21 is such that the portion 26^a of the "bucking bar" serves to shift the holding flux from the magnetic member 18 and thereby release the switch member 10 when a current of predetermined value flows through the "bucking bar" in the direction indicated by the arrows, while the portion 26^b serves to increase the holding effect upon the magnetic member 19 and thereby more firmly hold the switch member 11 in the circuit closing position. Conversely with the current flowing through the "bucking bar" in the opposite or reverse direction from that indicated by the arrows the portion 26^b serves to shift the holding flux from the magnetic member 19 to release the switch member 11 and the portion 26^a functions to more firmly maintain the magnetic member 18 in attracted engagement with the poles 20.

The manner in which each portion of the "bucking bar" functions to shift the flux from the magnetic members 18 and 19 is fully described and claimed in the Tritle reissue Patent No. 15,441 of August 29, 1922.

From the foregoing the operation of the circuit interrupter shown in Fig. 1 to afford overload protection to either an alternating current or a direct current will be clear. When the alternating current or the direct

current is increased to an abnormal value by the occurrence of short circuit or excessive overload, one or the other of the switch members 10 or 11, dependent upon the direction in which current flows through the "bucking bar" 26 at the instant of excessive current value, is released to permit the corresponding biasing spring 12 or 13 to quickly operate the respective switch member to the circuit interrupting position. This permits the interrupter to safely and successfully break the circuit in response to an excessive current flow in either direction in the circuit controlled by the interrupter.

In the modified arrangement shown in Figs. 3 and 4 the magnetic structure of the holding electromagnet is rearranged so that the holding flux for the poles 20 is supplied by the magnetizing winding 27, while the holding flux for the poles 21 is supplied by the magnetizing winding 28. Furthermore, the relative direction in which magnetizing flux is supplied to the poles 20 and 21 so that the poles have opposite polarities is indicated by the notations N, S, and N' S', in Fig. 3. With the polarity of the poles reversed the releasing conductor or "bucking bar" 26 is formed in a simple U shape and may be energized from the secondary of a current transformer 29 connected in the circuit controlled by the interrupter contacts 16 and 17. The U shaped "bucking bar" 26 serves to shift the flux in one or the other pair of poles 20 and 21 to release the cooperating magnetic members 18 and 19 in substantially the same manner as previously described. In this case, the predetermined flow of current through the portion 26^c of the releasing winding or "bucking bar" 26 in the direction indicated by arrows in Fig. 4 serves to shift the flux in the pair of poles 20 to release the magnetic member 18, while the flow of current through the portion 26^d of the "bucking bar" serves to increase the magnetic traction upon the member 19. With a flow of current through the releasing winding or "bucking bar" 26 in the reverse direction, the portion 26^d then shifts the holding flux from the magnetic member 19 and the portion 26^c increases the holding effect upon the magnetic member 18. As the holding flux is supplied to the poles 20 and 21 in the arrangement shown in Fig. 3 through separate magnetic flux paths, the possibility of interference between the opposite magnetic actions of the sections 26^c and 26^d of the "bucking bar" is effectively prevented.

While I have described a preferred embodiment of my invention, it should be understood that the apparatus shown is only illustrative and that the invention may be carried out by other means.

What I claim as new and desire to secure by Letters Patent of the United States is:—

1. A high speed circuit interrupter for an

- electric circuit adapted to carry current in either direction comprising a pair of cooperating independently movable switch members operable together into circuit closing engagement and biased apart to interrupt the circuit jointly controlled thereby, electromagnetic means providing separate flux paths for holding each of said members in the circuit closing position, and means for providing additional flux paths for the holding flux of said electromagnetic means to release one of said switch members for operation to interrupt the circuit jointly controlled thereby in accordance with its bias upon a predetermined current flow in one direction in the circuit controlled by the interrupter and to release the other of said switch members for operation to interrupt the circuit jointly controlled thereby in accordance with its bias upon a predetermined current flow in the reverse direction in the circuit controlled by the interrupter.
2. A high speed circuit interrupter for an electric circuit adapted to carry current in either direction comprising a pair of cooperating independently movable switch members operable together into circuit closing engagement and biased apart to interrupt the circuit jointly controlled thereby, electromagnetic means having a plurality of pairs of poles disposed between the switch members for separately holding said members in the circuit closing position, and means energized in accordance with the current in the circuit controlled by the interrupter and cooperating with said poles to release a corresponding one of said switch members for operation to interrupt the circuit jointly controlled thereby in accordance with its bias upon a predetermined current flow in each direction in the controlled circuit.
3. A high speed circuit interrupter for an electric circuit adapted to carry current in either direction comprising a pair of cooperating independently movable switch members operable together into circuit closing engagement and biased apart to interrupt the circuit jointly controlled thereby, electromagnetic means having a separate flux path for magnetically holding each of said switch members in the circuit closing position, and means responsive to the current in the circuit controlled by the interrupter for providing an additional path for the holding flux in a corresponding one of said flux paths upon a predetermined current flow in each direction in the controlled circuit and thereby permit the corresponding one of said switch members to operate out of engagement with the cooperating switch member to interrupt the circuit jointly controlled thereby in accordance with its bias.
4. A high speed circuit interrupter for an electric circuit adapted to carry current in either direction comprising a pair of co-
- operating independently movable switch members operable together into circuit closing engagement and biased apart to interrupt the circuit jointly controlled thereby and each having a movable magnetic member connected therewith, normally energized magnetic means having a separate pair of poles for holding each of said magnetic members when the corresponding switch member is operated to the circuit closing positions, and windings energized in accordance with the current in the circuit controlled by the interrupter associated with said magnetic means for providing a path for the holding flux thereof independently of a predetermined one of said magnetic members to effect the release of the corresponding one of said switch members upon a predetermined current flow in each direction in the controlled circuit.
5. A high speed circuit interrupter for an electric circuit adapted to carry current in either direction comprising a pair of cooperating independently movable switch members operable together into circuit closing engagement and biased apart to interrupt the circuit jointly controlled thereby, electromagnetic means including a pair of movable magnetic members operable into a predetermined spaced relation and each connected to a corresponding one of said switch members for separately holding said switch members in the circuit closing position, and windings interposed between said magnetic members and energized in accordance with the current in the circuit controlled by the interrupter to shift the magnetic holding flux from a corresponding one of said magnetic members upon a predetermined current flow in either direction in the circuit controlled by the interrupter to permit the corresponding switch member to operate out of engagement with the cooperating switch member in accordance with its bias to interrupt the circuit jointly controlled thereby.
6. A high speed circuit interrupter for an electric circuit adapted to carry current in either direction comprising a pair of cooperating independently movable switch members operable together into circuit closing engagement and biased apart to interrupt the circuit jointly controlled thereby, electromagnetic means having separate pairs of poles interposed between said members for electromagnetically holding said switch members together in the circuit closing position, and means energized in accordance with the current in the circuit controlled by the interrupter for oppositely varying the holding effect of said pairs of poles to effect the release of only one of said switch members for operation to interrupt the circuit jointly controlled thereby in accordance with its bias upon a predetermined current flow in each direction in the circuit controlled by the interrupter.
7. A high speed circuit interrupter for an

electric circuit adapted to carry current in either direction comprising a pair of cooperating independently movable switch members operable together into circuit closing engagement and biased apart to interrupt the circuit jointly controlled thereby, electromagnetic means including a pair of movable magnetic members each mounted upon a corresponding one of said switch members and electromagnetic means having separate pairs of poles disposed in spaced relation between the said switch members and cooperating with each magnetic member to hold the corresponding switch member in the circuit closing position when operated thereto, and windings ener-

gized in accordance with the current in the circuit controlled by the interrupter and interposed between each of said pairs of poles for shifting the holding flux from a corresponding one of said magnetic members upon a predetermined current flow in each direction in the circuit controlled by the interrupter to permit a corresponding switch member to operate out of engagement with the cooperating switch member to interrupt the circuit jointly controlled thereby in accordance with its bias. 20 25

In witness whereof, I have hereunto set my hand this second day of April, 1926.

FRANK ROBERSON.
